UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

LOOPER MECHANISM FOR SEWING MACHINES.

Application filed October 20, 1921. Serial No. 508,930.

The invention relates to new and useful improvements in looper mechanism for sewing machines, and more particularly to a looper mechanism which is adapted to be used in a work supporting arm.

An object of the invention is to provide a looper operating mechanism for a work supporting arm which is so constructed that the looper shaft which extends longitudinally of the work supporting arm is given a dwell in its oscillations when the looper is at the forward end of its stroke and substantially while said looper is being moved laterally to avoid the needle.

A further object of the invention is to provide a looper operating mechanism of the above type wherein the means for moving the looper shaft longitudinally for giving to the looper its needle avoiding movement is capable of adjustment so that the lateral stroke imparted to the looper may be varied.

A still further object of the invention is to provide a machine of the above type, wherein the work supporting arm is carried by and projects laterally from a vertically extending frame member into which the operating shaft extends.

These and other objects will in part be obvious and will in part be hereinafter more fully disclosed.

In the drawings which show by way of illustration one embodiment of the invention—

Figure 1 is a view partly in vertical section and partly in side elevation of a portion of a sewing machine embodying my improvements;

Figure 2 is a sectional view on the line 2—2 of Fig. 1;

Figure 3 is a sectional view on the line 3—3 of Fig. 1;

Figure 4 is a sectional view on the line 4—4 of Fig. 1;

Figure 5 is an enlarged longitudinal sectional view through the vertically extending member and the rear portion of the work supporting arm and showing the looper shaft operating mechanism in side elevation;

Figure 6 is a perspective view of the rocker for moving the looper shaft endwise and the collar connection to the shaft.

I have shown the invention as applied to a sewing machine of the type disclosed in the patent granted to Lansing Onderdonk, December 18, 1906, No. 839,077. Said machine has a frame member extending horizontally

and parallel with the overhanging arm. The machine has been illustrated only in part in the drawings and reference may be had to said patent for a better understanding of the complete machine.

The operating shaft extends into a vertically extending member which carries the work supporting arm. The looper is carried by a shaft which extends longitudinally of the work supporting arm and into the upper end of this vertically extending member. The means for operating the looper shaft for oscillating the loopers and for giving a lateral movement thereto is located in this vertically extending member and receive their movements from the operating shaft which projects into this vertically extending member. On the shaft is a rotating eccentric and between this rotating eccentric and a radially projecting arm carried by the looper shaft is a train of mechanism including toggle links which are so timed and disposed as to approach and pass slightly the dead center when the looper is at the forward end of its stroke, and thus it is that a dwell is given to the looper in its oscillations while the looper is in the needle thread loop. The looper shaft is moved endwise by a rock lever which is turned is oscillated by an eccentric strap co-operating with an eccentric on the operating shaft.

The eccentric strap has an adjustable connection with the rock lever so that the extent of oscillations imparted to the rock lever may be varied and thus the amount of lateral movement given to the looper may be varied.

Referring more in detail to the drawings, I have shown the invention as embodied in a machine which includes a horizontally extending frame member 1, and this horizontally extending frame member as more clearly shown in the Onderdonk patent above referred to, is parallel with the overhanging arm. Projecting vertically from this horizontally extending frame member 1 is a vertical frame member 2. Located in the horizontally extending frame member 1 is an operating shaft 3. This operating shaft, as clearly shown in the Onderdonk patent, is rotated from the main driving shaft. Said operating shaft 3 projects into the vertically extending frame member 2 and projecting laterally from the upper end of the vertically extending frame member 2 is a work supporting arm 4. This work supporting arm 4 is comparatively small in cross section and

is especially adapted for stitching garments having tubular parts.

The material being stitched is fed off from the end of the arm as the tube is formed. This is accomplished by a main feed dog 5 and an auxiliary feed dog 6. The material is held on the work support by a presser foot 7 indicated diagrammatically in dotted lines in Fig. 1. The machine may be provided with a plurality of needles and these needles are set abreast and positioned as indicated in dotted lines at 8. Co-operating with the needles beneath the work support is a single thread carrying looper 9. This thread carrying looper 9 is carried by a looper supporting shaft 10 which extends longitudinally of the work supporting arm 4 and is mounted for oscillation and endwise movement in bearings 11, 12 and 13. The main feed dog 5 is carried by a feed bar 14. This feed bar 14 is mounted on links 15 which are pivotally attached to a lever 16, fulcrumed at 17 and connected to an eccentric strap 18 which co-operates with an eccentric on the operating shaft 3. As this operating shaft rotates the lever 16 is oscillated and this gives the up and down movements to the feed bar 14. The feed bar 14, at the right-hand end thereof, as viewed in Figure 1, is mounted so as to rock on a pin 19 and this pin 19 is capable of sliding in slots in the upper portion of the bearing 12. The feed bar is moved endwise on this bearing 12 by means of a link 20, which is pivoted at 21 to the feed bar and at 22 to a slotted end of a lever 23. This lever 23 at its inner end is connected to an eccentric strap 24 which co-operates with an eccentric on the main shaft. Through this lever the feed bar is given its endwise movement.

The auxiliary feed dog 6 is carried by an auxiliary feed bar 25 which is mounted to slide on the main feed bar 14, so that the auxiliary feed bar is raised and lowered with the main feed bar. This auxiliary feed bar is moved back and forth by means of a lever 26 which is connected to the auxiliary feed dog at 27. This lever 26 has a fork at its lower end straddling a pin 28 which serves as a fulcrum pin for the lever. The lever is connected by a link 29 to the main feed bar 14, so that as the main feed bar moves back and forth it will oscillate this lever 26 and this imparts a movement to the auxiliary feed bar which may be different in extent from the movement imparted to the main feed bar.

This differential feeding mechanism which has been referred to briefly above forms no part of the present invention but is shown, described and claimed in my co-pending application Serial No. 508,931, filed of even date herewith and patented April 21, 1925, No. 1,534,132.

The looper supporting shaft 10 is oscillated for moving the looper into and out of the

needle thread loops. This is brought about by a link 30 which is connected to a ball 31 carried at the outer end of a radially extending arm 32 clamped to the looper supporting shaft 10. This radially extending arm 32 is formed integral with a slit sleeve which is clamped to the looper shaft by means of a bolt 33. The link 30 is connected at its lower end to a ball stud 34 carried by the arm 35 of a rock lever which is pivoted at 36 to the frame of the machine. This rock lever has a downwardly extending arm 37 which is pivoted at 38 to a link 39. The link 39 is pivoted at 40 to an arm or link 41 which is fixed to a short stub shaft 42 mounted in suitable bearings in the vertically projecting frame member 2. This link or arm 41 carries a ball-stud 43 to which an eccentric strap 44 is pivoted. This eccentric strap 44 co-operates with an eccentric 45 on the operating shaft 3.

When the radially extending arm 32 is moved downwardly the looper is moved forward into the needle loop and when it is lifted or raised upwardly then the looper is retracted from the needle thread loop. It will be readily seen that the links 39 and 41 constitute toggle links and they move from a point at one side of a line passing through the pivotal connection 38 and the center of the shaft 42 to a position substantially in said line or slightly to the other side thereof. When these links are in the position shown in Fig. 5, that is, with the toggle links buckled, the radial arm 32 is raised and the looper is at the rear end of its stroke. When these toggle links are in alinement, as shown in Fig. 1, then the looper is at the forward end of its stroke. It will be readily seen that the links approach a dead center and they pass said dead center line slightly and this occurs while the looper is at the forward end of its stroke, which gives to the looper a dwell at this time so that the looper moves forward into the needle thread loop and then comes substantially to a stop or dwell for a period of time and during this dwell it is moved laterally for its needle avoiding movement.

The needle avoiding movement is given to the looper by means of a rock lever 46. This rock lever 46 is shown in perspective in Fig. 6 of the drawings. It consists of a projecting arm 47 having a slot 48 therein and yoke arms 49-49. On the looper shaft 10 is a collar 50 which is loose on the shaft. This collar 50 carries projecting pins 51-51 which extend through the ends of the yoke arms 49-49 and on the ends of the pins are nuts 52-52. This rock lever 46 is mounted to oscillate freely on a short shaft 53 carried by the vertically projecting frame member 2.

Co-operating with the eccentric on the main shaft is an eccentric strap 54 and this eccentric strap 54 is connected to a ball 55

carried by the outer end of a short stud arm 56. This stud arm 56 is adjustably mounted in the slot 48 of the rock lever 46. Said stud is held in adjusted positions by means of a 5 nut 57. By adjusting this stud 56 the amount of movement imparted to the rock lever 46 may be varied. The collar 50 which freely engages the looper supporting shaft is mounted on said shaft between two spaced collars 10 58 and 59. These spaced collars are fixed to the shaft and this permits the shaft to oscillate freely in the collar 50, but any endwise movement of the collar 50 will cause an endwise movement to the looper shaft. The shaft 15 53 which carries the rock lever 46 is held from endwise movement in the vertically projecting frame member 2 by collars 60 and 61. The upper portion of the vertically projecting frame member 2 and the work supporting arm 4 is closed by a removable cover plate 62 which may be held in place in any suitable way. The side of the vertically projecting frame member 2 is cut to expose the parts of the looper operating mechanism and 20 this is closed by a cover plate 63. This gives ready access to the mechanism operated by the shaft 31 which imparts movements to the looper and also imparts movements to the feed dogs.

25 The operation of my device will be obvious from the description which has been given above. As the operating shaft 3 extending into the vertically projecting frame member 2 rotates it will oscillate the toggle links which 30 in turn will give to the looper supporting shaft an oscillation. These toggle links approach or cross a dead center as the looper reaches the forward end of its stroke and as a result the looper dwells when it gets into 35 the needle thread loop and remains in the dwell substantially while the lateral movements are imparted thereto. The first part of the backward movement of the looper is comparatively slow, and this gives ample time 40 for the needle to get down into the thread triangle. The backward movement of the looper increases in speed and the rear end of the looper movement is very rapid, said looper instantly starting forward to enter the needle 45 thread loop and this movement of the looper is very quick until the point of the looper is passed well into the looper thread loop, after 50 which the movement of the looper slows down until it comes to a dwell. These movements 55 insure the perfect entrance of the looper into the needle thread loop and the needle in turn into the thread triangle which causes the looper thread loop to be left on the needle. The lateral movements imparted to the looper 60 are derived from an eccentric on the shaft 3 and this is brought about through the rock lever having a slotted arm connection with the eccentric, so that the throw of the rock lever may be readily varied and thus the extent of lateral movement imparted to the 65 looper may be changed. The slot 48 in the rock lever is preferably cut so as to be concentric with the center of the operating eccentric therefor when the looper is on the side of the needle passed by the looper as it enters the 70 needle thread loop. Thus the looper may be set to pass very close to the needle and variations in the lateral throw of the looper will not change the position at which the looper passes the needle. 75

It is obvious that minor changes in the details of construction and arrangement of parts may be made without departing from the spirit of the invention as set forth in the appended claims. 80

Having thus described my invention, what I claim as new and desire to secure by Letters Patent, is:

1. The combination of a vertically extending frame member, a work supporting arm 85 projecting laterally therefrom, an operating shaft extending into said frame member, a looper supporting shaft extending longitudinally of said work supporting arm, a threaded looper carried thereby, means actuated by 90 said operating shaft for giving the looper supporting shaft an endwise movement, and independent means actuated by said operating shaft for oscillating said looper supporting shaft, said means including toggle links 95 movable toward and from a dead center, said toggle links being in substantial alinement when the looper is at the forward end of its stroke and during the endwise movement of the looper shaft. 100

2. The combination of a vertically extending frame member, a work supporting arm projecting laterally therefrom, an operating shaft extending into said frame member, a looper supporting shaft extending longitudinally of said work supporting arm, a threaded looper carried thereby, means actuated by 105 said operating shaft for giving the looper supporting shaft an endwise movement, and independent means actuated by said operating shaft for oscillating the looper shaft, said means including an eccentric, an eccentric strap, toggle links operated by said eccentric strap, a rock lever oscillated by the toggle links, and a link connecting the rock lever to 110 the looper supporting shaft, said toggle links being in substantial alinement when the looper is at the forward end of its stroke and during the endwise movement of the looper shaft. 115

3. The combination of a vertically extending frame member, a work supporting arm projecting laterally therefrom, an operating shaft extending into said frame member, a looper supporting shaft extending longitudinally of said work supporting arm, a threaded looper carried thereby, means actuated by 120 said operating shaft for giving the looper supporting shaft an endwise movement, and independent means actuated by the 125

operating shaft for oscillating the looper supporting shaft, said means including an eccentric on the operating shaft, an eccentric strap, an oscillating arm to which said eccentric strap is connected, a rock lever, a link connecting said rock lever with said oscillating arm, said oscillating arm and link being adapted to move into alinement when the looper is at the forward end of its stroke, a radial arm carried by and projecting laterally from the looper supporting shaft, and a link connecting said radial arm to the rock lever.

4. A sewing machine including in combination, a main frame structure, a rotatable shaft mounted therein, a vertical member attached at one end to said frame, a laterally projecting work arm mounted at the other end of said vertical member, a feeding mechanism including a four motion feed dog mounted in said work supporting arm, a looper supporting shaft extending longitudinally of said work supporting arm, a threaded looper carried thereby, means actuated by said operating shaft for giving the looper supporting shaft an endwise movement, independent means actuated by said operating shaft for oscillating the looper shaft, and means independent of said oscillating means for the looper shaft and actuated by said operating shaft for giving said feed dog its movements.

5. A sewing machine including in combination, a main frame structure, a rotatable shaft mounted therein, a vertical member attached at one end to said frame, a laterally projecting work arm mounted at the other end of said vertical member, a feeding mechanism including a four motion feed dog mounted in said work supporting arm, a looper supporting shaft extending longitudinally of said work supporting arm, a threaded looper carried thereby, means actuated by said operating shaft for giving the looper supporting shaft an endwise movement, an eccentric on said operating shaft, means operated thereby for oscillating the looper shaft, an independent eccentric on said operating shaft, means operated thereby for raising and lowering the feed dog, and means actuated from said operating shaft for moving the feed dog back and forth.

6. A sewing machine including in combination, a main frame structure, a rotatable shaft mounted therein, a vertical member attached at one end to said frame, a laterally projecting work arm mounted at the other end of said vertical member, a feeding mechanism including a four motion feed dog mounted in said work supporting arm, a looper supporting shaft extending longi-

tudinally of said work supporting arm, a threaded looper carried thereby, means actuated by said operating shaft for giving the looper supporting shaft an endwise movement, an eccentric on said operating shaft, means operated thereby for moving said looper supporting shaft endwise, an independent eccentric on said operating shaft, means operated thereby for oscillating said looper shaft, a third independent eccentric on said operating shaft, means operated thereby for raising and lowering said feed dog, and means actuated from said operating shaft for moving said feed dog back and forth.

7. A sewing machine including in combination, a main frame structure, a rotatable shaft mounted therein, a vertical member attached at one end of said frame, a laterally projecting work arm mounted at the other end of said vertical member, a feeding mechanism including a four motion feed dog, a looper mechanism including a four motion looper, four independent eccentrically set members carried by said main shaft, devices actuated by one of said members for moving the feed dog back and forth, devices actuated from another of said members for raising and lowering said feed dog, and devices actuated from another member for moving the looper into and out of the needle thread loop, and devices actuated from still another eccentric member for giving a lateral or needle avoiding movement to the looper.

8. The combination of a vertically extending frame member, a work supporting arm projecting laterally therefrom, an operating shaft extending into said frame member, a looper supporting shaft extending longitudinally of said work supporting arm and transversely across the said vertically extending frame member, said frame member having a bearing for the outer end of said looper shaft, a threaded looper carried by said shaft, means for oscillating said looper shaft from said operating shaft including an arm attached to said looper shaft back from the end thereof, and independent means for moving said looper supporting shaft endwise including an eccentric on the operating shaft, a sleeve on said looper shaft between said arm and the end bearing, spaced collars on the looper shaft for restraining the endwise movement of the sleeve on said looper shaft, a rock lever having an arm extending transversely of the frame member and connected to said eccentric, and a yoke extending lengthwise of said frame member and pivotally connected to said sleeve.

In testimony whereof, I affix my signature.

JAMES R. MOFFATT.
